CLAIM

The ornamental design for tray for supporting and dispensing golf balls, as shown and described.

DESCRIPTION

FIG. 1 is a perspective view of tray for supporting and dispensing golf balls showing my new design;

FIG. 2 is a top plan view thereof;

FIG. 3 is a bottom plan view thereof;

FIG. 4 is a front elevation view thereof;

FIG. 5 is a rear elevation view thereof; and,

FIG. 6 is a right side elevation view thereof, the left side elevation view thereof being a mirror image.
